UNITED STATES PATENT OFFICE.

A. G. SHAVER, OF NEW HAVEN, CONNECTICUT.

ERASER AND BURNISHER.

Specification forming part of Letters Patent No. **58,684**, dated October 9, 1866.

To all whom it may concern:

Be it known that I, A. G. SHAVER, of New Haven, in the county of New Haven and State of Connecticut, have invented a new and useful Improvement in Erasers and Burnishers; and I do hereby declare the following to be a full, clear, and exact description of the same, reference being had to the accompanying drawings, in which—

Figures 1, 2, 3, and 4 exhibit modifications of my invention.

My invention consists in the construction of erasers, desk-knives, and implements of that character designed and adapted for the erasure of ink from paper or parchment with metallic or mineral burnishers, in a manner substantially as set forth in the following description.

Many forms of erasers have been made in order to meet the demands of individual taste, and, notwithstanding the peculiar merits of these various forms, very many persons prefer the old-fashioned ordinary style, as that shown in the blade of Fig. 1.

It is very well known that a good burnisher is as necessary to the efficiency of the implement as is a good blade, and it is also well known that a good and efficient burnisher cannot be constructed except from some material possessing great hardness and capable of receiving a very high polish. The most common materials for such purpose are steel and agate, and I construct the burnishers attached to my erasers of those or other suitable materials.

Eraser-blades are frequently set into turned handles, as in Fig. 3, and with such I use round or oval pointed tips *a*, made of hardened steel or other suitable material, as shown in Fig. 3. These tips are provided with a tang projecting into the handle, or with a hole, into which the end of the handle is inserted. Upon the ordinary flat handles, as in Fig. 1, I place a corresponding tip, as shown at *b*, which may be solid, with a tang or blade extending into the handle, or it may be merely a shell placed over the end and secured in any suitable way. If the tip is to be applied to a knife with movable blade, as shown in Fig. 2, the tip and back-spring may very conveniently be made in one piece, as shown at *c*, though that form is not essential.

To serve as a paper folder or cutter, I make the flat tip somewhat thinner and longer, as shown at *d* in Fig. 4. One edge is then preferably made thinner and sharper than the other, as the sharper edge will cut paper better and the blunt one will fold it better.

Having described my invention, what I claim as new, and desire to secure by Letters Patent, is—

In combination with the blade or handle of an eraser or desk-knife, a burnisher-tip, substantially as described.

A. G. SHAVER.
